UNITED STATES PATENT OFFICE.

NORMAN W. GAYLE, OF BEECH GROVE, INDIANA, ASSIGNOR TO CHARLES N. VAN CLEAVE, OF INDIANAPOLIS, INDIANA.

COIN-CONTROLLED LOCK.

Application filed October 5, 1923. Serial No. 666,816.

My said invention relates to a coin-controlled lock for telephone booths and the like, and it is an object thereof to provide an improved device of this character which shall be very simple in construction and inexpensive to manufacture.

A further object of the invention is to provide a device of the character described in which the shaft carrying the outer knob also carries a shutter for the coin-slot, thus dispensing with relatively complicated trains of mechanism often used in devices of this character.

Another object is to provide a simple means for selecting a coin of proper size to operate the device.

Another object is to provide a simple and certain means for discharging the coin when its function in the lock has been performed.

Another object is to provide means for counting the coins visible from the outside but provided with a normally closed shutter operable only from the inside of the lock.

Another object is to provide improved means whereby the bolt may be operated again and again from the outside after insertion of a coin until the door has been once opened and closed, all without requiring insertion of another coin.

Still another object is to provide means for closing the coin-slot when the lock is out of order or when for any other reason it is not to be used.

Referring to the accompanying drawings which are made a part hereof and on which similar reference characters indicate similar parts,

Figure 1 is an elevation of the device,

Figure 2, a section on line 2—2 of Fig. 1, certain parts being omitted for clear disclosure,

Figure 3, a front elevation of the operating parts in normal position,

Figure 4, a similar view after a coin has been inserted and the outer knob turned,

Figure 5, a similar view after the inner knob has been turned to release the coin,

Figure 6, a detail of the bolt, and

Figure 7, a detail of the rocking actuator.

In the drawings reference character 10 indicates the removable outer plate of a casing attached to a rear plate 11 by screws 12. The rear plate is secured to a door 13 by screws 14. The face plate has an opening

at its lower end for removal of the money collected, said opening being closed by a door 15 having a lock 16, of any conventional or desirable form. Above the door 15 is an opening for a rockshaft 17 (Fig. 3) on which is a knob 18 at the front side of the door 13.

The plate 10 has a coin-slot 19 and a slot 20 for exposing to sight the numerals on a counting device hereinafter described. The plate carries a shutter 21 for slot 20, the shutter being guided by pins 22, 23 and having at its lower end a finger piece 24 accessible only when the door 15 is open. By this means it is possible to check up the receipts and yet keep from outside parties any knowledge of either total receipts or receipts over a definite period which knowledge might be availed of, for example, by persons desiring to steal the coin in the device and wishing to do so only when a maximum sum is present.

At the upper righthand corner of the casing is a lock 25 available to an operative without the use of a coin. A rockarm 25' projects from the lock into the casing in position to engage the upward projection 40 of bolt 35 (Fig. 3) so that the bolt can readily be retracted by an appropriate key, the lock preferably being of the type known as the Yale lock. The radial part of the rockarm is indicated in Figures 3 to 5 in dotted lines, while an inwardly projecting finger or crank is shown in solid lines for clearer illustration.

The back plate 11 supports the main elements of mechanism and for this purpose is provided near its upper end with a bracket 26 bearing a counting device 27. To the right of this bracket is a post 28 having a rocker 29 pivotally attached to its front end by a screw 30. One arm of the rocker has a rounded end interposed between the forks of an operating member 31 of the counting device 27. The other arm is slotted for engagement with a pin 32 on a plate 46 (Fig. 3).

Below the bracket 26 is a bracket in the shape of a fin 33 (Figures 2 and 4) standing perpendicular to the face of the plate 11. This fin is provided with an opening for the reduced rearward extension 34 of a bolt 35. The fin is cut away at its upper righthand corner to provide a limit stop for a pawl 36.

A spring 37 is secured to a pin 38 on the fin at one end and at the other end to the free extremity of pawl 36.

At its rear end the pawl 36 is pivotally secured by a screw 36' to a bracket 39 which is fixed to plate 11 and forms a guide for bolt 35. The bolt has at its upper side a pin 40 (Fig. 6) limiting its movement in the direction toward the keeper 41. A spring 42 (Fig. 3) located between the fin 33 and the shoulder formed at the junction of the extension 34 with the body of the bolt normally holds the bolt in projected position.

15 About midway between its ends the plate
11 carries a bracket in the form of a bridge
43. The shaft 17 is journaled at one end in
this bridge and is supported at the other
end by a spindle having a reduced end enter-
20 ing a cavity at the inner end of shaft 17 the
spindle supporting an inner knob 44.

Shaft 17 supports a plate 45 oscillating therewith said plate being loosely mounted and readily removable. When the plate is reversed from the position shown it serves as a guard to prevent entry of dirt or other material or objects through the coin slot as in transit or in storage. When in the position shown it has no effect on the action of the lock.

At the inner side of bracket 43 a plate 46 is mounted on shaft 17, this plate serving as a shutter for the coin-slot and having at 46' a pin and at 47 a slot adapted to register 35 with the coin-slot 19 in one position of the plate. It is so mounted that in its extreme position (Fig. 4) its lower edge rests on the edge of bracket 43 thus limiting the movement of plate 46 in this direction. Its 40 rearward movement is limited by engagement of the inclined lower edge portion 48 (Fig. 4) with bracket 43. A spring 49 serves to retract the plate 46 on the shaft 17. A pin 32 on the plate engages in the 45 slot in arm 29 to operate the counting device and also rides under the lower surface of pawl 36 to lift it until the pin comes opposite the notch at 51 (Fig. 5) whereupon the pawl drops into locking engagement with 50 plate 46.

An actuator 52 in the form of a rockarm (Fig. 7) is fixed to shaft 17 for oscillation therewith. The actuator has two arms 53, 54 separated by a slot 55. The arms have lugs 56, 56' coacting to support a coin on the inclined face of the actuator and a notch 57 in arm 54 provides clearance for the pin 46' on plate 46 next to the slot 47. The bolt 58 has depending arms 59 and 60 (Fig. 6) adapted to move through the slot 55. A spring 65 acts on shaft 17 to hold the actuator in the position shown in Fig. 3.

The shaft of the knob 44 carries a rock-arm 61 lying parallel to the actuator 52 and in contact with the inclined under side

thereof when the latter is in its normal inclined position and in contact with said actuator for a considerable part of its length in the illustrated embodiment of the invention. The shaft 17 and the spindle of knob 44 are coaxial so that such engagement persists in all positions of the parts. The upper end of the arm extends into a lateral notch at 62 on bolt 35 in position to force the bolt back while at the same time the actuator is moved in the same direction. The parts are so proportioned and arranged that the coin will not only be released but also will be forced out of operative position by arm 60 which normally has its upper or left-hand face in the same plane as the left-hand face of actuator 52 (Fig. 3) but which advances ahead of such face in operation (Fig. 5). At the same time also a pin 63 projecting perpendicularly toward the front of the lock and here shown as mounted on a lateral extension of rockarm 61 acts against the lower cam surface of tail 64 of pawl 36. The knob 18 turns shaft 17, plate 45 and actuator 52 whenever it is moved, irrespective of the presence of a coin. The knob 44 turns independently of knob 18 and oscillates the rockarm 61. If there is a coin on the actuator, the bolt 35 and the plate 46 move with knob 18 as do parts actuated by plate 46; but a full movement of knob 44 always rocks actuator 52 and pawl 36, while the bolt is retracted by the upper end of rockarm 61, the movement of the actuator being less in this case than when it is rocked through the medium of the pawl 18. The bolt 35 has a movement of translation imparted to it by the arm 61 such that it travels ahead of the actuator 52 by reason of the greater distance of the bolt from the center of oscillation, by reason of which an equal arcuate movement will result in a greater movement of translation than at points nearer said center.

In the operation of my device, the parts being in the position of Fig. 3 a coin is inserted through slots 19 and 47. If the coin is of insufficient size it will pass down the inclined face of the actuator without effect, the relatively higher position of the rear lug 56 as compared with lug 56' aiding in this selecting action and the righthand face of arm 59 being so spaced as to facilitate egress of thin coins. The finger 59 is spaced from the face of the actuator 52 far enough so that a coin of insufficient thickness cannot be used to operate the device as by lodging on the lug 56' and the lug at the lower end of the finger, but will slide down the face of the actuator into the coin box, it being understood that the coin must be small enough so as not to lodge on the two lugs 56 and 56', e. g. a nickel or a penny. Should the coin be of proper size and thickness it will be arrested on the inclined face by lugs 130

56, 56'. The knob 18 being turned the actuator will act through the coin against arm 59 to retract the bolt and also through the coin against the pin 46' to move plate 46 to the left so as to close slot 19. The movement of plate 46 acts through pin 32 to lift pawl 36 and to swing rockarm 29, thus actuating the counter and when the pin reaches slot 51 locking the plate 46 against return movement, spring 37 drawing the pawl down against the shoulder on fin 33.

The coin is now held on the actuator by the force of the spring on extension 34 of the bolt and the coin-slot is closed, all as indicated in Fig. 4; therefore shaft 17 may be rocked back and forth until the bolt is released and the door opened. On closing the door the bolt is forced back and releases the coin either permissively by the movement of arm 59 from the face of the actuator or positively by the push of arm 60. The bolt is now free from external control but may be moved by operating knob 44 at the inner side of the door. The shutter 46 still closes the coin-slot.

When the knob 44 is turned as explained above, the actuator 52 is moved in a direction to release the coin if it were still in position, the bolt is retracted, the pawl is withdrawn from pin 32 against the tension of spring 37 and the shutter is thrown back by its spring 49 thereby also returning the rockarm 29 to place and completing the counting action. If the door should stick the bolt may be retracted repeatedly by turning knob 44.

It will be evident to those skilled in the art that my device may be modified in various respects and may be applied to various uses without departing from the spirit of the invention the true scope of which is indicated in the appended claims, and therefore I do not limit myself to the specific embodiment shown in the drawings and described in the specification but only as indicated in said claims.

Having thus fully described my said invention, what I claim as new and desire to secure by Letters Patent is:

50 1. In a coin-controlled device, a casing having a coin-slot, a rockarm, means on the rockarm adapted to sustain a coin independently, a detent, a shutter for the coin slot, means whereby said coin moves the shutter into latching engagement with the detent, and means whereby the shutter may be released from the detent, substantially as set forth.

60 2. In a coin-controlled device, a casing having a coin-slot, a rockarm, means on the rockarm adapted to sustain independently a coin of suitable character, a shutter for the coin-slot, pivoted coaxially with the rock-arm, a detent for the shutter, and means whereby said coin moves the shutter into

latching engagement with the detent, and means for releasing the shutter, substantially as set forth.

3. In a coin-controlled device, a casing having a coin-slot, a shaft, a rockarm on the shaft having means to support a coin inserted through said slot, a shutter pivoted on said shaft, a lug on the shutter coacting with a coin in the rockarm to close the shutter, a detent on the casing engageable with the shutter, a shaft alined with the first but movable independently thereof, and means operated by the last-named shaft for disengaging the detent from the shutter, substantially as set forth.

4. In a coin-controlled device, a casing having a coin-slot, a spring-bolt projecting from the casing, a shaft, a rockarm on the shaft having means to support a coin inserted through said slot, a shutter pivoted on said shaft, a lug on the shutter coacting with a coin on the rockarm to close the shutter, a detent in the casing engageable with the shutter to lock the same, a shaft alined with the first but movable independently thereof, a rockarm on the shaft engaging the bolt, and a pin extending laterally from the rock-arm into engagement with a cam face on said detent for releasing the shutter, substantially as set forth.

5. In a coin-controlled lock, a casing having an attaching plate, a support in the casing, a shaft journaled in the support and extending through the front of the casing, a shutter loosely pivoted on the shaft, said shutter having a slot adapted to register with a coin slot in the front of the casing, a rock arm fixed to said shaft and connections between the rock arm and the shutter whereby the rock arm closes the shutter through a coin previously inserted into said coin slot, means for supporting a coin during such operation, a detent for holding the shutter in closed position and a spring for returning the shutter to open position and means extending through the rear of the casing for releasing the detent, substantially as set forth.

6. In a coin-controlled lock, a casing having an attaching plate, a bridge-piece having feet attached to the back of the casing and a body parallel to the front of the casing, a shaft journaled in the bridge-piece, a shutter loosely pivoted on the shaft, said shutter having a slot adapted to register with a coin-slot in the casing, means on the rock-arm adjacent to said slot for supporting a coin, a rockarm fixed to said shaft, and connections between the rockarm and the shutter whereby the rockarm closes the shutter through a coin inserted into said coin-slot the closing movement of the shutter being limited by engagement with the body of the bridge-piece, substantially as set forth.

65 7. In a coin-controlled device, a casing

- having a coin-slot, a pivoted shutter having a slot adapted to register with the coin-slot, means operating through a coin for closing said shutter, a lug on the shutter, a detent 5 for engagement with said lug to keep the shutter closed, means whereby the lug may be released from the detent, and counting means operated by said lug, substantially as set forth.
- 10 8. In a coin-controlled lock, a casing having a coin slot, a shutter for the slot, a latch for the shutter, a bolt, a pair of aligned shafts in the casing, a rock arm fixed to one shaft adapted to retract said bolt and close 15 the shutter by pressing against a coin previously inserted through said slot, and a rock arm on the other shaft adapted to retract the bolt and move the latch to release the shutter from closed position, substantially as set forth.
9. In a coin-controlled lock, a casing having a coin-slot, a shutter for the slot, a bolt, a pair of aligned shafts in the casing, a rock-arm fixed to one shaft adapted to press a 20 coin inserted through said slot against the bolt to retract the same and simultaneously against the shutter to close it, means for supporting the coin during such operation, a detent to hold the shutter in closed position, 25 and rockarm on the other shaft adapted to engage the bolt and to release said detent, substantially as set forth.
10. In a coin-controlled lock, a rocking actuator having a coin engaging face, a slide- 30 able bolt having a coin-engaging face co-operating with that on the actuator and a coin ejecting face so arranged that when the bolt is retracted the coin engaging face of the bolt will move away from that of the 35 actuator to release the coin and the ejecting face will engage the coin to push it off the actuator, and means to support the coin during such operations, substantially as set forth.
- 40 45 11. In a coin-controlled lock, a spring-bolt slideable horizontally, a keeper for the bolt downwardly projecting forks fixed to the bolt, a rocking actuator having an inclined face for supporting a coin between said forks, whereby movement of the bolt by the keeper operates to advance the forks away from said inclined face thereby releasing 50 said coin, and means for supporting the coin prior to such releasing action, substantially as set forth.
- 55 12. In a coin-controlled lock a bolt having forks, an actuator having an inclined face adapted to support a coin between said forks, and spaced lugs on said actuator 60 adapted to support a coin of predetermined size only, substantially as set forth.
- 65 13. In a coin-controlled lock a bolt having forks, an actuator having an inclined face adapted to support a coin between said forks, and spaced lugs on said actuator 70 adapted to support a coin of predetermined size only, the lug on the near side being lower than that on the far side, substantially as set forth.
- 75 14. In a coin-controlled lock, a back-plate, a bolt having a reduced rear extension, a bracket slidably supporting the front end of the bolt, a bracket slidably supporting the extension, a spring between the extension and a shoulder on the bolt, a coin-slot in the outer casing of the lock, a shutter therefor, means to actuate the shutter after insertion of a coin, a pawl on the first-named bracket adapted to hold the shutter in closed position, a stop on the second bracket to engage the free end of the pawl and limit its movement, means whereby the shutter may be disengaged from said pawl, and a spring on the latter bracket for drawing the pawl toward the stop, substantially as set forth. 80
- 85 15. In a coin-controlled device, a casing having a coin-slot, a rockarm, means on the rockarm adapted to sustain a coin independently, a detent, a shutter for the coin slot, means whereby said coin moves the shutter into latching engagement with the detent, and means whereby said detent may be released, substantially as set forth. 90
- 95 16. In a coin-controlled device, a casing having a coin-slot, a rockarm, means on the rockarm adapted to sustain independently a coin of suitable character, a shutter for the slot pivoted coaxially with the rockarm, a detent for the shutter, means whereby said coin moves the shutter into latching engagement with the detent, and means whereby said shutter may be released, substantially as set forth. 100
- 105 17. In a coin-controlled device, a casing having a coin-slot, a pivoted shutter having a slot adapted to register with the coin-slot, means operating through a coin for closing said shutter, a lug on the shutter, a detent for engagement with said lug to keep the shutter closed, counting means operated by said lug, and means for releasing the detent, substantially as set forth. 110
- 115 18. In a coin-controlled lock, a spring-bolt slideable horizontally, downwardly projecting forks fixed to the bolt, a rocking actuator having an inclined face for supporting a coin between said forks, and means for rocking the actuator to press a coin against one fork to retract the bolt the other fork serving to eject the coin on retraction of the bolt as the door closes, substantially as set forth. 120
- 125 19. In a coin-controlled device, a casing having a coin-slot, a rock arm having an inclined coin-sustaining face, spaced low projections on said face engaging the lower edge of the coin, and a spring bolt finger in the path of movement of said coin when moved by said rock arm, said finger spaced far enough from the sustaining face when the 130

rock arm is at rest, so as not to aid the low projections in retaining a coin of undesirable thinness, substantially as set forth.

20. In a coin-controlled device, a casing having a coin-slot, a rock arm having an inclined coin-sustaining face, spaced projections on said face engaging the lower edge of the coin, and a spring bolt finger opposite said face to contact with the upper face of the coin to aid the projections in retaining a coin and to be in the path of movement of said coin with said rock arm to make the bolt operable by the rock arm, substantially as set forth.

21. In a coin-controlled device, a casing having a coin-slot, a rockarm having an inclined flat face to receive a coin from said slot, a shutter for said slot, a projection on the shutter against which a flat face of the coin is pressed to actuate the shutter, means to hold the shutter in position to close the slot, and means to release it from such position, substantially as set forth.

22. In a coin-controlled lock, a casing having a coin-slot, a bolt, a shutter for the slot, a shaft extending crosswise of the casing, a rockarm on the shaft having means on one face forming the sole support of a coin lying in a plane extending lengthwise of the shaft, and connections acting through a coin on the rockarm to operate the bolt and the shutter, substantially as set forth.

23. In a coin-controlled lock, a casing having a coin-slot, a rockarm, a pivoted shutter for the slot operable from the rockarm through a coin inserted in said slot, means for supporting such a coin in operative position relatively to said shutter, a detent for the shutter on a pivot parallel to that of

the shutter, means at the front of the lock for operating the rockarm, and means at the rear of the lock for releasing said detent, substantially as set forth.

24. In a coin-controlled lock for doors, a casing having a coin slot, a shaft operable from the front of the casing, a rock arm on the shaft, a spring bolt actuating finger adapted to be retracted by the rock arm after insertion of a coin through the slot, said finger arranged to keep the coin from being released during the return movement of the rock arm after the said retraction, so that the retraction can be repeated by the rock arm, means coacting with said finger to support the coin, and means whereby the bolt may be retracted directly from the inside of the door, substantially as set forth.

25. In a coin controlled lock, a casing having an attaching plate, a bridge-piece having feet attached to said plate and a body parallel to the front of the casing, a shaft journaled in the bridge-piece, a shutter pivoted on the shaft said shutter having a slot adapted to register with a coin slot in the casing, means adjacent said slot for supporting a coin said means being movable by said shaft, connections operable through a coin so supported to close the shutter, locking and releasing means for the shutter, and a spring for opening the shutter the opening movement of the shutter being limited by engagement with the body of said bridge-piece, substantially as set forth.

In witness whereof, I have hereunto set my hand at Indianapolis, Indiana, this 1st day of September, A. D. nineteen hundred and twenty-three.

NORMAN W. GAYLE.
